UNITED STATES PATENT OFFICE.

ALBERT DAVID LEWIS, OF ATLANTA, GEORGIA.

DESIGN FOR A BOTTLE.

Application filed June 5, 1926. Serial No. 17,956. Term of patent 14 years.

To all whom it may concern:

Be it known that I, ALBERT D. LEWIS, a citizen of the United States, residing at Atlanta, in the county of Fulton and State of Georgia, have invented a new, original, and ornamental Design for a Bottle, of which the following is a specification, reference being had to the accompanying drawing, forming part thereof.

The single figure is a side elevation view of a bottle, embodying my new design.

I claim:—

The ornamental design for a bottle, substantially as shown.

In testimony that I claim the foregoing as my own, I have hereto affixed my signature.

ALBERT DAVID LEWIS.
